UNITED STATES PATENT OFFICE.

ENRIQUE A. TOUCEDA, OF ALBANY, NEW YORK.

ART OF METALLURGY.

No. 823,560.

Specification of Letters Patent.

Patented June 19, 1906.

Application filed January 28, 1905. Serial No. 243,016.

To all whom it may concern:

Be it known that I, ENRIQUE A. TOUCEDA, a citizen of the United States, residing at Albany, county of Albany, and State of New York, have invented certain new and useful Improvements in Art of Metallurgy, of which the following is a specification.

The invention relates to such improvements; and it consists of the novel construction and combination of parts hereinafter described and subsequently claimed.

Reference may be had to the accompanying drawings and the reference characters marked thereon, which form a part of this specification.

Similar characters refer to similar parts in both figures therein.

Figure 1 of the drawings is a central vertical longitudinal section of a coal-burning reverberatory furnace adapted for the practice of my invention. Fig. 2 is a view, partly in elevation and partly in cross-section, of the same.

The principal objects of this invention are to secure greater economy in time and fuel and to permit without increased fuel expense a wider range in the chemical composition of the material under treatment in the operation of metallurgical furnaces.

Other objects will appear in connection with the following description.

The invention consists in the method of procedure hereinafter set forth, whereby heat of comparatively low intensity escaping from a metallurgical furnace is converted into electrically-generated heat of comparatively high intensity and returned within the furnace.

The invention is applicable in the use of various kinds of metallurgical furnace adapted for burning solid, liquid, or gaseous fuel, and it is particularly adapted for use in a non-regenerative reverberatory furnace in the process of preparing iron for malleable castings, in connection with which it will be more particularly described.

In the known types of non-regenerative reverberatory furnace, whether adapted for solid, liquid, or gaseous fuel, less, perhaps, than ten per cent. of the total heat units available in the fuel is communicated to the materials on the hearth, the remainder of such heat usually escaping through the stack, as is well understood by those skilled in the art. It has been thus far found impracticable to profitably utilize this enor-

mous waste of heat in non-regenerative furnaces intermittently operated, as in preparing iron for malleable castings, and such furnaces in use to-day show no material improvement whereby a greater percentage of heat units can be utilized from the fuel than was possible in the original type of furnace of this class many years ago, with only the exception that air is now judiciously introduced over the grate-bridge wall to insure more perfect combustion, it being a notorious fact that less improvement has been made in the type of reverberatory furnace referred to than in any other furnace in which metallurgical operations are conducted.

By the use of my invention I am able to save and return within the furnace in highly efficient form a large percentage of such heat as would otherwise be lost, resulting in a large saving in time and fuel in the operation of the furnace, as well as adapting it for a wider range of use, as will be hereinafter more fully set forth.

Referring to the drawings, wherein is shown a preferred form of apparatus for the practice of my invention, 1 is the fire-box, provided with the grate 2, adapted for burning solid fuel, as coal, the heated gases from the fire-box being deflected by the arched ceiling 4 toward the hearth 5, all constructed and adapted to operate in substantially the same manner as the ordinary coal-burning non-regenerative reverberatory furnace.

Between the hearth-chamber and the stack 6 is located a steam-boiler 7, which may be of any known type adapted for the generation of steam by the heat derived from the gases escaping from the hearth-chamber to the stack, which gases after passing said boiler are permitted to escape through the stack. A steam-supply pipe 8 leads from the boiler 7 to a steam-engine 9, which may be of any known form and which is connected with a dynamo 10 to operate the same. Said dynamo is connected by wires 11 through a switchboard 12 in circuit with a pair of arc-forming electrodes 13, which project interiorly of the hearth-chamber in proximity to the hearth and in position for the heat from said arc to be efficiently exerted upon the materials under treatment on the hearth. Any desired number of pairs of such electrodes may be thus connected with said dynamo, and the switchboard 12 may be provided with the usual devices for regulating

and controlling the supply of electrical energy to the electrodes.

Any known means may be employed to convert the waste heat from the furnace into electrical energy, and any known form of electrical heating apparatus capable of withstanding the heat of the furnace may be employed. The electrodes 13 shown are preferably carbons, adjustably mounted at 14. The adjustment of the electrodes may be accomplished in any known manner, and their position may be changed from time to time to adapt them for most advantageous use in the particular metallurgical operation in hand.

It will thus be seen that I am able to effectively supplement the heat due to the reverberatory action of the furnace by the heat generated by the electric heater within the hearth-chamber, which electrically-generated heat is of great intensity and highly efficient, enabling me to secure from a given supply of fuel the effectiveness of a greater number of heat units and a greater intensity of heat than has heretofore been found possible in fuel-burning metallurgical furnaces.

It will be observed that such portion of the electrically-generated heat as may be ineffective upon the materials on the hearth is not wholly lost, but in passing to the stack again serves to heat the boiler, and a large percentage thereof is again returned within the furnace through the electric heating device.

Aside from the saving in time and fuel accomplished by this invention in the operation of the reverberatory furnace the invention greatly enlarges the field of usefulness of the furnace, due to the fact that it permits a much more perfect command over the furnace than was heretofore possible, permitting greater liberties to be taken with the chemical composition of the material under treatment, with a resultant large saving in time required for treatment, as the intensity, location, and quantity of heat can be regulated in a manner best adapted for the kind of material under treatment and an increased output secured; due to the saving in time.

By the term "furnace" I intend to include a single furnace element or a plurality of bat-

tery of such elements, only one of which is shown in the drawings, and I consider as coming within the scope of my invention the conversion of heat emanating from any part of such a furnace into electrically-generated heat within any part thereof.

I make no claim herein to the apparatus herein disclosed for the practice of my invention, as the same forms the subject of another application by me, Serial No. 290,391, filed December 5, 1905, as a division of the present application.

What I claim as new, and desire to secure by Letters Patent, is—

1. That improvement in the art of metallurgy which consists in converting into electrical energy heat emanating from a metallurgical furnace, and converting said electrical energy into heat within the furnace.

2. That improvement in the art of metallurgy which consists in converting into electrical energy heat passing from the hearth of a reverberatory furnace, and converting said electrical energy into heat adjacent to the hearth within the furnace.

3. That improvement in the art of metallurgy which consists in converting into electrical energy heat passing from the hearth of a non-regenerative reverberatory furnace, and converting said electrical energy into heat within the furnace.

4. That improvement in the art of metallurgy which consists in converting into electrical energy heat emanating from a reverberatory furnace, and forming by said electrical energy an electric arc adjacent to the hearth within the furnace.

5. That improvement in the art of metallurgy which consists in converting into steam energy heat emanating from a metallurgical furnace, converting said steam energy into electrical energy, and converting said electrical energy into heat within the furnace.

In testimony whereof I have hereunto set my hand this 25th day of January, 1905.

ENRIQUE A. TOUCEDA.
